UNITED STATES PATENT OFFICE.

WILLIAM F. BOAST, OF CASPER, WYOMING.

TYPE-BAR HOLDER.

1,263,026.

Specification of Letters Patent. Patented Apr. 16, 1918.

Application filed April 4, 1917. Serial No. 159,736.

To all whom it may concern:

Be it known that I, WILLIAM F. BOAST, a citizen of the United States, residing at Casper, in the county of Natrona and State of Wyoming, have invented certain new and useful Improvements in Type-Bar Holders, of which the following is a specification.

This invention relates to improvements in printing devices, in which provision is made for adjusting the type to control the distances between the lines, and has for one of its objects to simplify and improve the construction and increase the efficiency and utility of devices of this character.

Another object of the invention is to provide a simply constructed device wherein means are provided for supporting a plurality of type bars carrying lines of type, and arranging them to be adjusted to control the distances between the bars without structural change in the device.

With these and other objects in view, the invention consists in certain novel features of construction, as hereinafter shown and described and then specifically pointed out in the claims; and in the drawings illustrative of the preferred embodiment of the invention—

Figure 1 is a longitudinal sectional view of a printing-press device with the improved type-bar and type-bar holding device applied.

Fig. 2 is a detached perspective view from beneath of a portion of one of the type-bars;

Fig. 3 is a detached perspective view from beneath of a portion of one of the type-bar supports;

Fig. 4 is an end elevation of the parts shown in Fig. 1;

Fig. 5 is an enlarged perspective view from beneath of a portion of the type-bar holding portion of the device;

Fig. 6 is an enlarged detail view of a portion of the device, illustrating a modification in the construction.

Corresponding and like parts are referred to in the following description and indicated in all the views of the drawings by the same reference characters.

The improved device is designed more particularly for printing matter for temporary use, such as bills of fare for hotels, restaurants, lunch rooms and the like which are changed several times each day, and is designed to enable these changes to be quickly

made without loss of time or the necessity of structural change in the device.

The improved device may be employed for printing statements of various kinds which are required to be frequently changed, such as price lists and the like, and it is not desired therefore to limit the invention in any manner in this respect.

The improved device includes a base member or block 10 of any suitable size and of any suitable material, the block being larger than the largest sheet upon which the printed matter is to be impressed. Rigidly connected to the upper face of the member 10 are metal strips 11 upturned at the ends 70 as shown at 12—13, the members 11 with their upturned ends providing means for coupling the base member 10 to the type bar supporting portion of the printing device.

For the purpose of illustration the supporting member is represented at 14 and preferably with inwardly sloping side edges as shown in Fig. 1. The upturned terminals 12 of the members 11 are inclined inwardly toward and engage flatly against the inclined adjacent edge of the member 14. The members 13 are spaced a considerable distance from the adjacent inclined edge of the member 14, and one of the members 13 is forked, and pivoted at 15 between the forked portions is a locking member 16. The pivot 15 is located at one side of the center of the member 16 near one end, whereby a cam face 17 is produced which is constructed to be pressed against the adjacent inclined face of the member 14 when the member 16 is disposed in its lower position as shown in Figs. 1 and 4. The member 10 is provided with a recess indicated at 18, into which the member 16 enters when disposed in its lower position. By this arrangement the member 10 is firmly locked in position relative to the member 14 and prevented from lateral displacement thereby, while the member 16 and the recess 18 are caused to coact to prevent longitudinal displacement between the parts. The other upturned end 13 of the other member 11 is provided with a threaded aperture to receive a binding screw 19 which bears against the adjacent inclined face of the member 14. The locking bar 16 of the set screw 19 thus coacts to rigidly couple the member 10 to the supporting member 14, while at the same time the member 10 and its attachments may

100
105
110

be easily removed and attached when required.

Any suitable means may be employed for actuating the supporting member 14 to cause the impressions to be made upon the sheets of paper, but for the purpose of illustration a conventional inking and impression device is shown, comprising an ink pad of suitable construction, represented as a whole at 20, and a yieldable bed member 21 upon which the sheet to be printed is placed. A lever device represented as a whole at 22, is pivoted at 23 to the frame-work 24 which supports the pad 20 and the bed member 21, and is likewise pivoted at 25 to bracket devices 26 extending from the platen member 14.

The lever devices 22 are coupled at their upper ends by a hand grip member 27. By this arrangement it will be obvious that the supporting member 14 may be arranged as shown in full lines in Fig. 1 and in Fig. 4 in position to impress the type upon the pad 20, and likewise adapted to be disposed in the position shown in dotted lines in Fig. 1 to dispose the platen member above the bed 21 to complete the printing action.

Attached to the lower face of the base member 10 are a plurality of type-bar holding devices, arranged side by side and in parallel relation as illustrated in Figs. 4, 5 and 6. Each holding device is pressed or bent from a metal strip substantially into L shape, whereby webs 28-29 are produced and extending at right angles to each other. The holding strips are attached to the lower face of the member 10 with the webs 28 bearing against the latter and preferably in engagement edge to edge. The webs 29 are thus supported at right angles to the member 10 and in spaced relation. In Figs. 4 and 5 each of the webs 29 is formed with an extension portion 30 which is bent inwardly toward the web 28 and in flattened V shape as shown more clearly in Fig. 5, the V shaped portions forming guides for the type-bars. The type-bars are preferably formed in two portions, a supporting portion 31 of resilient sheet metal bent into channel shape as shown more clearly in Figs. 2 and 3, with one side web further bent to form a flat V shaped channel or depression 33 to receive the rib 30 of the portion 29 of the support, and with a plurality of apertures 33' in the connecting web, as shown in Fig. 3. The type bearing portion 32, preferably of a rubber compound or like material, usually employed in rubber stamps, is disposed upon the perforated face of the member 31 and secured thereto by vulcanizing, a portion of the stock or bed of the type bearing portion entering the apertures and thus "locking" the member 32 to the member 31. By this arrangement the type-bars may be inserted either endwise between the webs 29 and held in place by the coaction of the portions 30 of the webs 29 and the

channels 33 of the type bars, or the members 31 may be forced bodily into spaces between the portions 29, the channeled web of the member 31 yielding to a sufficient extent to permit the channel 33 to engage the rib 30. 70

Each type-bar may thus be lifted bodily from its bed or inserted therein without disturbing the remaining bars. By arranging the holding device 28-29 in close proximity it will be obvious that the type-bars may be arranged at any required distance apart, and any required number employed. If the lines of the matter to be printed is in close relation then the spaces between the holding members will all be occupied by the type-bars, but if the printed matter is to be "displayed," or the lines spaced one from the other, then only the required number of the type-bars will be employed, and spaced as required. 80

In printing bills of fare, for instance, the spaces between the lines of printed matter is of considerable width, so that comparatively few of the type-bars will be employed and spaced at the required intervals, so that when the sheet which has been previously printed with the names of the different articles, such as soup, fish, entrées, roasts, dessert, extras and the like, is deposited upon the bed member 21 with one end against the gage 34 and the member 10 with its type bars containing the names of the various articles to be served arranged in proper order and first impressed upon the pad 20 to receive the ink, and then moved into the position shown in dotted lines in Fig. 1 and in contact with the sheet upon the bed 21, the latter will be instantaneously "printed." It will thus be obvious that as many sheets of paper as may be required can be expeditiously printed. It will also be obvious that the printed matter may be very quickly changed when required. The type-bars will be made up to contain the names of various dishes to be served, or arranged to contain matter which may be frequently required, so that the labor required to change the matter to be printed is materially lessened. 100

In Fig. 6 a modification is shown in the form of the projecting portion 30, which consists in substituting therefor a rib device 35 bent from the material of the web 29, while the portion 32 of the type-bar is formed with a channel corresponding to the shape of the rib 35, but this does not constitute a departure from the invention. The improved device is simple in construction, can be inexpensively manufactured, and applied without material structural change to operating devices of various forms and 110 shapes. 120

Having thus described the invention, what is claimed as new is:

1. In a device of the class described, a supporting base, a plurality of holding mem- 130

bers each including coacting webs in angular relation transversely, one web of each holding member being connected to the base and the other webs directed substantially in parallel relation and provided respectively with a longitudinally directed guide rib, and type bars each having coacting resilient webs to engage between the webs of the holding members, one of said resilient type bar webs 10 having a channel to engage the guide rib of one of the holding members.

2. A device of the class described comprising a supporting member having an operating means attached thereto, a base member 15 detachably coupled to said supporting member, a plurality of coacting holding members connected to said base member in spaced relation and each provided with a longitudinally directed guide rib, and type-bars 20 gaging between said holding members and

each having a yieldable web formed with a longitudinal guide channel engaging the adjacent guide rib.

3. A device of the class described including a base member, a plurality of holding members each including coacting webs in angular relation transversely, one web of each holding member being connected to the base member and the other webs directed in parallel relation to each other and each provided with a reversely beveled extension directed toward the base and forming a guide rib, and type bars each having coacting resilient webs to engage between the webs of the holding members, one of said resilient type bar webs having a channel to engage the projection of the guide rib.

In testimony whereof I affix my signature.

WILLIAM F. BOAST. [L. s.]
